UNITED STATES PATENT OFFICE

LORIN D. McCLEARY, OF INDIANAPOLIS, INDIANA

INTERNAL COMBUSTION ENGINE

Application filed September 6, 1929. Serial No. 390,741.

My invention relates to improvements in internal combustion engines and more particularly to that class of improvements which employs rotary motion in the functioning of their working parts, and the objects of my invention are to provide mechanism that will increase the ratio of crank leverage to the stroke of the piston, that, when desired, will permit such proportional combination of its functions as to operate on the Otto or four cycle principle in such manner as to produce an explosion in each cylinder during each revolution of the main or drive shaft, that will more flexibly absorb the power impulse from the cylinder for working force, that will employ higher piston speed at any speed of the drive shaft as compared to the standard type of engine, that will operate by rotary motions as a means of neutralizing vibration caused by reciprocating pistons and other working parts, that will permit of the elimination of gears and cam-shaft, when desired; that will simplify construction, shorten the length and lighten the weight as compared to the standard forms of engines, and lessen the strain on their working parts and frame, that will supply an air cooling process for the cylinders and that will obtain higher thermal and mechanical efficiencies than obtains in internal combustion engines commonly in use, and other objects.

I attain these objects by the mechanism illustrated in the accompanying drawings in which, Fig. 1 is a back view of the engine, and Fig. 2 is a cross sectional view on the line A A, Fig. 1.

Similar numerals refer to similar parts throughout the several views.

The sides 1 1, secured to the base 2, with the bolts 3 3, constitute the main framework of the engine.

The fixed crank-shaft 4, is secured to the frame side 1, by means of the sleeve 5, and the key 6. The rotatable frame 7 7 8, has provided in its side 8, the bearing 9, and has fixed to its opposite side the drive-shaft 10, by means of the bolts 11 11. The drive-shaft 10, is adapted to turn in the bearing 12, which is secured to the inner facing of the other

main frame side 1, by the bolts 13 13, and the bearing 9 is fitted to the journal of the fixed crank shaft 4, thus producing bearings for the rotatable frame 7 7 8, to rotate on the main frame 1 1 2.

Fixed to the rotatable frame 7 7 8, are the cylinders 14 14, which are provided with pistons 15 15. The crank-shaft 16, is journaled in the rotatable frame 7 7 8, by means of the bearings 17 17. One piston 15, and the crank-pin 18 are connected to the master connecting rod 19, and the other piston 15, is connected to the sleeve pin 20, by the connecting rod 21, while the other crank-pin 22, of the crank-shaft 16, is connected to the crank-pin 44, of the fixed crank-shaft 4, by the connecting rod 23, and the caps 24 24, and the bolts 25 25. Cast on the sides of the cylinders 14 14, are the valve chambers 26 26, into which are fitted the intake pipes 27 27, and the exhaust pipes 28 28. On the outer surface of the bearing 12, are the valve push-rod cams 29 29, on which the rollers 30 30, travel as the frame 7 7 8 rotates, thereby lifting the push-rod cams 31 31, and the poppet valves which are provided in the valve chambers 26 26, while the reaction of the valve push-rods is produced by the springs 32 32, which are compressed between the push-rod guides 33 33 and the push-rod spring seats 34 34.

The intake drumhead 36, is fixed to the sleeve 5, and the outer ends of the intake pipes 27 27, communicate with the intake drum 35, which is fixed to the rotatable frame side 8, and turns around the drumhead 36, into which is fitted the intake feed pipe 37.

Cast on one cylinder 14, are the lugs 38 38, to which are secured the balance weights 39 39, by the bolts 40 40. Through the sides of the power chambers 41 41, are set the spark plugs 42 42, to which are attached the ignition circuit wires 43 43.

Any convenient means of housing, lubrication, ignition or starting mechanism may be used on this engine, or a plurality of crank-shafts having any angular arrangement of crank throws may be employed in its operation.

As shown in the drawings, this engine is equipped with valve mechanism to operate on

the Otto or four cycle principle and in operation it functions as follows:

A starting impulse is applied to the crank-shaft 16, causing it to rotate in a rightward direction in the bearings 17 17, which simultaneously causes reciprocation of the pistons 15 15, in the cylinders 14 14, and the functioning of the valve mechanism while the revolving of the crank-pin 22, tends to increase the dimension from its axis to the axis of crank-pin 44, which is opposed by the connecting rod 23, thereby transferring the power impulse to rightward circumferential motion at the bearings 17 17 and thus causing the rotatable frame 7 7 8, with its assembly to revolve in a rightward direction about its axis. Concomitantly with this functioning the fluid for combustion is supplied to the cylinders through the feed intake pipe 37, the intake drum 35, the revolving sections of the intake pipes 27 27, and valve chambers 26 26, while the continued rotation of the crank-shaft 16, is maintained by the expansive pressures in the cylinders and the burnt gases are discharged through the exhaust pipes 28 28.

I claim:

1. The combination of a frame rotatable on an axis, a crank-shaft journaled in said frame in parallel alignment with the axis of said frame, a pivot fixed in relation to said axis and in the plane of rotation of said frame, a member having one end pivotally attached to a crank-pin of said crank-shaft and the other end pivotally attached to said fixed pivot.

2. The combination of a frame rotatable on an axis, a pivot fixed in relation to said axis and lying in the plane of rotation of said frame, a crank-shaft journaled in said frame in parallel alignment with the axis of said frame, a member having one end pivotally attached to a crank-pin of said crank-shaft and the other end pivotally attached to said fixed pivot, a cylinder fixed to said frame in radial relation to said crank-shaft, a piston provided in said cylinder, a connecting-rod connecting said piston to a crank-pin of said crank-shaft.

3. The combination of a frame rotatable on an axis, a crank-shaft journaled in said frame in parallel alignment with the axis of said frame, a pivot fixed in relation to said axis and lying in the plane of rotation of said frame and positioned without the orbit of said crank-shaft, a member having one end pivotally attached to a crank-pin of said crank-shaft and the other end pivotally attached to said fixed pivot, a cylinder fixed to said frame in radial relation to said crank-shaft, a piston provided in said cylinder, a connecting-rod connecting said piston to a crank-pin of said crank-shaft.

4. The combination of a frame having two spaced sections, a crank-shaft longitudinally disposed between said sections and having a

portion of its journal fixed to one of said sections, a bearing provided in the other of said sections and in alignment with said fixed crank-shaft, a rotatable frame having two spaced sections, a shaft fixed to one of said sections and extending outward therefrom, a bearing provided in the other of said sections and in alignment with said shaft, the bearing and the shaft of said rotatable frame sections being adapted to the journal of the said fixed crank-shaft and the bearing of the first mentioned frame respectively, said rotatable frame being adapted to rotate on the first-mentioned frame and around the aforesaid fixed crank-shaft by means of the bearings thus formed and described, a rotatable crank-shaft journaled in said rotatable frame in parallel alignment with the axis of said rotatable frame, a member having one end pivotally attached to the crank-pin of said fixed crank-shaft and its other end pivotally attached to a crank-pin of said rotatable crank-shaft, a cylinder fixed to said rotatable frame in radial relation to said rotatable crank-shaft, a piston provided in said cylinder, a connecting-rod connecting said piston to a crank-pin of said rotatable crank-shaft.

5. The combination of a frame having two spaced sections, a crank-shaft longitudinally disposed between said sections and having a portion of its journal fixed to one of said sections, a bearing provided in the other of said sections and in alignment with said fixed crank-shaft, a rotatable frame having two spaced sections, a shaft fixed to one of said sections and extending outward therefrom, a bearing provided in the other of said sections and in alignment with said shaft, the bearing and the shaft of said rotatable frame sections being adapted to the journal of the fixed crank-shaft and the bearing of the first mentioned frame respectively, said rotatable frame being adapted to rotate on the first-mentioned frame and around the aforesaid fixed crank-shaft by means of the bearings thus formed and described, a rotatable crank-shaft journaled in said rotatable frame and in parallel alignment with the axis of said rotatable frame, a member having one end pivotally attached to the crank-pin of the afore-mentioned fixed crank-shaft and its other end pivotally attached to a crank-pin of said rotatable crank-shaft, a plurality of cylinders fixed to said rotatable frame and in radial relation to said rotatable crank-shaft, pistons provided in said cylinders, a master connecting-rod connecting one of said pistons to a crank-pin of said rotatable crank-shaft, individual connecting-rods connecting the other of said pistons to sleeve-pins fixed in radial order around the crank pin sleeve of the master connecting rod.

LORIN D. McCLEARY.

CERTIFICATE OF CORRECTION.

September 6, 1932.

Patent No. 1,876,532.

LORIN D. McCLEARY.

It is hereby certified that error appears in the printed specification of the above numbered patent requiring correction as follows: Page 2, line 13, for "rightward circumferential" read "leftward rotary"; and line 16, for "rightward" read "leftward"; and that the said Letters Patent should be read with these corrections therein that the same may conform to the record of the case in the Patent Office.

Signed and sealed this 20th day of December, A. D. 1932.

M. J. Moore,
Acting Commissioner of Patents.
